UNITED STATES PATENT OFFICE

LOUIS V. ARONSON, OF NEWARK, NEW JERSEY, ASSIGNOR TO ART METAL WORKS, INC.,
A CORPORATION OF NEW JERSEY

DESIGN FOR A COMBINED CIGARETTE CONTAINER AND PYROPHORIC LIGHTER

Application filed January 14, 1930. Serial No. 34,126. Term of patent 14 years.

To all whom it may concern:

Be it known that I, LOUIS V. ARONSON, a citizen of the United States, residing at Newark, in the county of Essex and State of New Jersey, have invented a new, original, and ornamental Design for a Combined Cigarette Container and Pyrophoric Lighter, of which the following is a specification, reference being had to the accompanying drawing, forming part thereof wherein:

Figure 1 is a plan view looking at the top of the combined cigarette container and pyrophoric lighter;

Fig. 2 is an elevational view of the front wall of said combined cigarette container and pyrophoric lighter;

Fig. 3 is an elevational view of the rear wall of said combined cigarette container and pyrophoric lighter;

Fig. 4 is an elevational view of one of the end walls of said combined cigarette container and pyrophoric lighter; and

Fig. 5 is a plan view looking at the bottom of the combined cigarette container and pyrophoric lighter.

I claim:

The ornamental design for a combined cigarette container and pyrophoric lighter substantially as shown.

LOUIS V. ARONSON.
